UNITED STATES PATENT OFFICE.

GEORGE P. WINSALL, OF BURLINGTON, WISCONSIN.

SILO.

1,076,729.

Specification of Letters Patent.

Patented Oct. 28, 1913.

Application filed February 18, 1913. Serial No. 749,134.

To all whom it may concern:

Be it known that I, GEORGE P. WINSALL, a citizen of the United States, residing at Burlington, in the county of Racine and State of Wisconsin, have invented a new and useful Silo; and I do hereby declare the following to be a full, clear, and exact description of the invention, such as will enable others skilled in the art to which it appertains to make and use the same.

This invention relates to silos, and particularly to a new and useful sectional roofing therefor.

As an object of the invention, it is the aim to provide a sectional roofing, each section being V-shaped having a hinged point. These hinged points are adapted to swing inwardly when the sections of the roofing are thrown upwardly and outwardly.

Another object of the invention is the provision of pivoted bars upon the sections to hold the pointed portions in position when the sections of the roofing are closed, and when the sections of the roofing are open, said pivoted bars brace the sections in order to hold them open.

Another object of the invention is the provision of annular bands at the top of the silo to reinforce the same where the hinges of said sections are arranged.

A feature of the invention is the provision of a galvanized facing for each section, which is constructed of any suitable material such as wood or other fiber. Each section is provided with a suitable shield.

In practical fields, the various features or parts of the improved silo roofing may necessitate alterations, to which the patentee is entitled, provided the alterations fall within the scope of what is claimed.

The invention comprises further features and combination of parts, as hereinafter set forth, shown in the drawings and claimed.

In the drawings:—Figure 1 is a vertical sectional view through a silo, showing the improved roofing as applied with the same closed. Fig. 2 is a similar view, showing the roofing opened. Fig. 3 is a sectional view on line 3—3 of Fig. 1, showing the overlapped feature of the sections. Fig. 4 is a view showing the front and back of one of the sections. Fig. 5 is a plan view of the roofing.

Referring more particularly to the draw-

ings, 1 designates the cylindrical portion of a silo or grain bin, however, the contour of the same may be suitably varied. Adjacent the upper portion of the silo, a pair of bands 2 and 3 is arranged; the band 2 is arranged on the interior, while the band 3 is arranged on the exterior. These bands are provided for the purpose of reinforcing the silo, where the hinges 4 are located. The roofing 5 of the silo is constructed of a plurality of V-shaped sections 6, hinged to the silo by the hinges 4. Said sections 6 are provided with pivoted supplemental pointed sections 7 hinged at 8. When the sections 6 of the roofing are swung upwardly and outwardly as shown in Fig. 2, the pointed sections 7 hang downwardly upon the inner faces of the sections 6. The sections 6 are arranged in the positions shown in Fig. 2, in order that the silo may be filled easily.

Fulcrumed, pivoted or otherwise suitably connected at 10 to the sections 6 are latch bars 11, and when the sections 6 are arranged as shown in Fig. 2, the bars 11 are disposed transversely, so that the ends of each bar 11 will extend between the pointed sections 7 and the adjacent section 6, thereby holding the sections in such position as shown in Fig. 2.

Arranged transversely of the cylindrical silo 1 is a timber or beam 12 having lugs 13 at each end to form the U-shaped parts 14, which arch over the upper edge of the cylindrical silo 1. This transverse beam or timber 12 is fixed or otherwise keyed to the center pole 15, as shown at 16, in order to support the pole in a vertical position. This pole is constructed with an annular recess 17, the purpose of which will appear hereinafter.

When the silo roofing is closed as shown in Fig. 1, the bars 11 are arranged in order to support the pointed sections 7, the extremities 19 of which rest in the annular recess 17 of the center pole. One edge of each of the sections 6 and each of the pointed sections 7, is provided with a shield to overlap the edge of the adjacent sections 6 and 7. This shield is denoted by the numeral 20.

The sections 6 and 7 are provided with galvanized facing 22, and shields 24 to protect the hinges 8 against the grain or other material from becoming lodged about the hinges.

The sections 6 are provided with gable ex-

tensions 25, in order to insure the carrying of the rain and the like beyond the side of the silo.

It is to be ascertained from the foregoing 5 that there has been devised a simple, efficient and durable sectional roofing for silos, and one which has been found desirable and practical, owing to the fact that the grain has a free passage when filling the same into 10 the silo, for the reason that the transverse timber or beam 12 including the center pole 17 may be removed.

The invention having been set forth, what is claimed as new and useful is:—

15 In combination, a cylindrical silo, a series of substantially triangular shaped roof sections, said sections being hinged to the side of the silo adjacent the top thereof, each sec-

tion comprising two hinged parts, each part which is hinged to the silo having a bar pivoted thereto and disposed substantially transversely of the section and engaging the opposite ends of the upper hinged part of the two adjacent sections to hold the sections in open positions against closing, said bars 20 adapted to be arranged lined with the sections to support the upper hinged parts when the sections are closed.

In testimony whereof I have signed my name to this specification in the presence of 25 two subscribing witnesses.

GEORGE P. WINSALL.
